UNITED STATES PATENT OFFICE.

THEODORE JELSEMA AND HARRY RUSSELL, OF SAN FRANCISCO, CALIFORNIA.

DESIGN FOR A SOUVENIR EMBLEMATIC GATE.

46,804.

Specification for Design.

Patented Dec. 29, 1914.

Application filed September 19, 1914. Serial No. 862,606. Term of patent 3½ years.

To all whom it may concern:

Be it known that we, THEODORE JELSEMA and HARRY RUSSELL, citizens of the United States, residing at San Francisco, in the county of San Francisco and State of California, have invented a new, original, and ornamental Design for a Souvenir Emblematic Gate, of which the following is a specification, reference being had to the accompanying drawing, forming part thereof.

The figure is a front elevation of a souvenir emblematic gate, showing our new design.

We claim:

The ornamental design for a souvenir emblematic gate as shown.

THEODORE JELSEMA.
HARRY RUSSELL.
